CLAIM

The ornamental design for a cap for aerosol can, as shown and described.

DESCRIPTION

FIG. 1 is an elevational front view of a cap for aerosol can; and,

FIG. 2 is a perspective view of a cap for aerosol can.

The side opposite that shown in FIG. 2 is a mirror image thereof. The rear and interior portions of the cap for aerosol can that are not shown in FIGS. 1 and 2 form no part of the claimed design.
